William N. Dow,

Attorney.

UNITED STATES PATENT OFFICE.

JOHN COX, OF ALBANY, NEW YORK.

APPARATUS FOR DRAWING LIQUIDS FROM BARRELS.

SPECIFICATION forming part of Letters Patent No. 288,978, dated November 27, 1883.

Application filed August 31, 1883. (No model.)

To all whom it may concern:

Be it known that I, JOHN COX, of the city and county of Albany, in the State of New York, have invented certain new and useful 5 Improvements in Apparatus for Drawing Liquids from Barrels, Casks, &c., of which the following is a specification.

My invention relates to improvements in the construction of sleeve-taps or pipes that are insertible in either the head or side of casks, barrels, and other vessels, and which are so arranged that compressed air may by them be conveyed into the cask or other vessel in such manner that the air, acting upon the surface 15 of the liquid contained in the cask, will cause the liquid to pass up into and out of a discharge-pipe which is contained in the sleeve-tap through which the compressed air is introduced into the cask.

20 The objects of my improvements are, first, to simplify the construction of the sleeve-tap and render it less liable to be injured during the operation of driving it into a cask; and, second, to provide proper facilities for the 25 rapid removal and insertion of the discharge-pipe out of and into the sleeve-tap. I attain these objects by means of the mechanism illustrated in the accompanying drawings, which form part of this specification, and in which—

30 Figure 1 is a longitudinal section of my sleeve-tap and coupling device, the discharge-pipe being shown in elevation; Fig. 2, a front elevation of the coupling device or clamp; Fig. 3, an inverted plan view, and Fig. 4 a side elevation of the same; and Fig. 5, a horizontal section of the sleeve-tap at the line $x-x$ on Fig. 1.

As represented in the drawings, the sleeve-tap A is made conical on its lower portion for the purpose of obtaining a close joint between 40 it and the circumference of holes of various sizes that are formed in casks and other vessels for the insertion of devices for drawing the contained liquid therefrom. The bore of the lower portion of said sleeve-tap is tapered to 45 conform to the exterior shape of said tap until the head a is reached, when the bore is reduced to the diameter of the discharge-pipe that is inserted therethrough. The head a is provided with an external groove, a', for receiving the coupling device herein described; and the said groove may be made in the form shown in the full lines of Fig. 5, or it may be entirely

circumferential, as indicated by the complementary dotted line in said figure. The head a has in its upper end a chamber or recess for 55 containing an annular packing, B, of india-rubber or other elastic material, and the outer diameter of said packing should be made to fit snugly into the chamber for containing it, and its inner diameter should be sufficient to permit the discharge-pipe to slide through it without difficulty. Below the head a the body of the sleeve-tap A has a side branch, a², into which a nipple, C, is secured. Said nipple is formed so that an india-rubber or other flexible tube can be slipped thereon; and the inner end of said nipple is provided with an inlet-valve, c, which I preferably make of a single thickness of oiled silk that is drawn across the inner end of the hole through said nipple. 70

The discharge-pipe D is inserted longitudinally through the sleeve-tap A, and is fitted to slide easily through the bore of the head a and the annular packing B. Said discharge-pipe must be of sufficient length to reach closely to 75 the bottom of the cask, and may be extended outwardly to any required length. The lower end of said pipe is closed over and provided with perforations that will permit liquids to flow into the bore of the pipe. 80

My coupling device is composed of the following parts: A hub or nut, E, containing an internal screw-thread, is connected by the side limbs, e, to a U-shaped flange, e', that is fitted to slide into the groove a' of the sleeve-tap A. A hollow screw, F, is fitted to screw into the hub E, and is provided on its outer end with a head, f, or other means, by which a rotatory motion can be imparted to said screw. A presser-foot, f', is loosely fitted to 90 the lower end of the screw F, and is attached thereto in such manner that said screw can be rotated without imparting a like motion to the presser-foot. The screw F and its attached presser-foot are bored out, so that the discharge-pipe D can slide freely through them. 95

The sleeve-tap A, detached from the discharge-pipe D and the coupling device, is inserted into a suitable opening formed in the cask or other vessel from which the liquid is 100 to be drawn, and is secured therein by striking said tap on its head a with sufficient force to make it hold by frictional contact. The coupling device is next attached to the sleeve-

tap A by sliding the flange e' into the groove a' , and the discharge-pipe D is then pushed down through the screw F, presser-foot f' , packing B, and head a until said pipe is inserted a sufficient distance into the cask. The screw F is then turned down until the annular packing B is pressed down and expanded laterally to produce an air-tight joint around the discharge-pipe D. The nipple C is connected 10 by means of a suitable tube to any proper air-compressing device, and by means of the latter air is forced through the space between the tapered bore of the sleeve-tap A and discharge-pipe D into the interior of the cask, where, by 15 its action upon the surface of the contained liquid, it will cause the latter to pass out through the discharge-pipe D. This apparatus can be readily removed from the cask by first slackening up the screw F, so as to permit 20 the discharge-pipe D to be drawn out, and then detaching the coupling device, after which the sleeve-tap A can be easily displaced.

I do not broadly claim an apparatus composed of a sleeve-tap provided with an elastic packing, a valved inlet air-opening, and a discharge-pipe, as I am aware that such a device is old in manifold forms; but 25

What I claim as my invention is—

The sleeve-tap A, provided with a head, a, whose bore is just large enough to permit the 30 discharge-pipe D to slide therein, the said head being provided with an external groove, a' , and a recess for containing the annular elastic packing B, as herein set forth, in combination with the discharge-pipe D, contained in the 35 sleeve-tap A, as herein described, and a coupling device composed of the nut E, having an open-sided flange, e' , formed to engage in the groove a' , and a hollow screw, F, all constructed and arranged to operate as herein specified. 40

JOHN COX.
